UNITED STATES PATENT OFFICE

153,356

DESIGN FOR AN AIRPLANE CONTROL WHEEL

Albert T. Holt, Burbank, Calif., assignor to Lockheed Aircraft Corporation, Burbank, Calif.

Application February 28, 1947, Serial No. 137,233

Term of patent 14 years

(Cl. D71—1)

To all whom it may concern:

Be it known that I, Albert T. Holt, a citizen of the United States, residing at Burbank, in the county of Los Angeles and State of California, have invented a new, original, and ornamental Design for an Airplane Control Wheel, of which the following is a specification, reference being had to the accompanying drawings, forming a part thereof.

Figure 1 is a perspective front view of an airplane control wheel, embodying my design.

Figure 2 is a perspective rear view thereof.

I claim:

The ornamental design for an airplane control wheel, substantially as shown.

ALBERT T. HOLT.
